UNITED STATES PATENT OFFICE.

LOUIS STOCKSTROM, OF ST. LOUIS, MISSOURI, ASSIGNOR OF ONE-HALF TO
CHARLES A. STOCKSTROM, OF SAME PLACE.

DESIGN FOR A VAPOR-STOVE.

SPECIFICATION forming part of Design No. 22,551, dated June 20, 1893.

Application filed April 10, 1893. Serial No. 469,828. Term of patent 7 years.

To all whom it may concern:

Be it known that I, LOUIS STOCKSTROM, of the city of St. Louis, in the State of Missouri, have invented and produced a new and original design for Vapor-Stoves, of which the following is a specification, reference being had to the accompanying drawing, forming a part thereof.

The drawing is a perspective view of a vapor stove, showing the design.

The leading features of my design consist of a parallelopipedon shaped body, a rectangular top plate projecting over the body, a back plate above the top plate, a rectangular cap-plate surmounting the back plate, a door in front and a panel beneath said door, and a long panel extending the height of said door and panel to one side thereof.

1 represents the body of a vapor stove, parallelopipedon shape, having an inclosed lower portion 1^a.

2 are feet forming supports for the body.

3 are side walls of the body.

4 is a projecting rectangular top plate above the body. 25

5 are spider frames located in the top plate openings.

6 are cylindrical portions within the body.

7 is a back plate above the top of rectangular shape. 30

8 is a cap-plate surmounting the back plate.

9 is a cylindrical body above the cap-plate.

10 is a door in front of the body, and which extends part way only across the stove. 35

11 is a panel beneath the door 10.

12 is a panel extending the height, or substantially the height of the door 10 and panel 11, and at one end thereof, on the other side of the stove.

I claim as my invention— 40

The design for a vapor stove, substantially as shown and described

LOUIS STOCKSTROM.

In presence of—

ALBERT M. EBERSOLE,
E. S. KNIGHT.
